US0D1041148S

(12) **United States Design Patent** (10) **Patent No.:** **US D1,041,148 S**
Qibo (45) **Date of Patent:** **** Sep. 10, 2024**

(54) **HEEL INSERT**

(71) Applicant: **Huang Qibo**, Quanzhou Fujian (CN)
(72) Inventor: **Huang Qibo**, Quanzhou Fujian (CN)
(**) Term: **15 Years**
(21) Appl. No.: **29/929,105**

(22) Filed: **Feb. 20, 2024**

(51) LOC (14) Cl. **02-04**
(52) U.S. Cl.
USPC **D2/961**

(58) **Field of Classification Search**
